ONE-PIECE BOAT

Rolf A. Robison, 1176 N. Jordan Ave., Provo, Utah
Filed Oct. 7, 1958, Ser. No. 765,753
4 Claims. (Cl. 9—6)

The present invention generally relates to a boat construction and more particularly to a boat which is constructed of one piece of material thereby eliminating the usual joints and seams which are subject to leaking and which also define weakened structural points in the boat.

The primary object of the present invention is to provide a boat constructed of one piece of material that is accomplished by folding a single piece of material in a predetermined manner to form a boat which has no seams or joints, at least below the water line.

Another object of the present invention is to provide a boat construction of one piece in which the contours of the bottom area of the boat are such that the water drag of the boat at high speeds is reduced to a minimum.

A further object of the present invention is to provide a one-piece boat construction having a minimum water drag especially at high speed which is extremely simple in construction, easy to make, rugged and long lasting and extremely inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a side elevation of the boat of the present invention;

FIGURE 2 is a top plan view of the construction of FIGURE 1 with portions thereof broken away illustrating the details of construction;

FIGURE 3 is a rear elevation of the boat with a part of the transom broken away;

FIGURE 4 is a front elevation of the boat;

FIGURE 5 is a bottom plan view of the boat;

FIGURE 6 is a longitudinal, vertical sectional view taken substantially upon a plane passing along section line 6—6 of FIGURE 2 illustrating further details of construction of the boat;

FIGURE 7 is a plan view of the blank from which the boat is formed showing the various fold or crease lines;

FIGURE 8 is a transverse, vertical sectional view taken substantially upon a plane passing along section line 8—8 of FIGURE 1 illustrating the cross-sectional shape of the boat adjacent the forward end thereof;

FIGURE 9 is a partial perspective view showing one step in forming the boat from the single piece of material;

FIGURE 10 is a detailed sectional view taken substantially upon a plane passing along section line 10—10 of FIGURE 6 illustrating the fold at the junction between the bow portion of the boat and the main portion; and

FIGURE 11 is a detailed sectional view taken substantially upon a plane passing along section line 11—11 of FIGURE 6 illustrating the joint between the adjacent edges of the forward deck of the boat.

Referring now specifically to the drawings, the numeral 10 generally designates the boat construction of the present invention which for the purposes of descrip-

2

tion will be divided generally into a bow section designated by the numeral 12, a main hull or central hull section 14 and a stern area 16. FIGURE 7 illustrates the blank from which the boat 10 is constructed and the blank is generally designated by the numeral 18 and is substantially rectangular in configuration. In order to define the construction of the boat, each area of the blank 18 will be given a reference numeral and described and this reference numeral will be employed throughout the final construction of the boat shown in the various other views. The blank 18 may be constructed of any suitable material such as sheet metal or various metallic alloys.

The general rectangular blank 18 is separated into a bow section generally designated by the numeral 20, a central hull section 22 and a stern section 24. The bow section 20 is connected with the central hull section 22 by a transversely extending fold line 26 which is inclined from the center slightly towards the bow end of the blank 18. The stern section 24 is separated from the central hull section 22 by a transverse fold line separated into outer segments 28 which are perpendicular to the side edges of the blank and inner sections 30 which are substantially parallel to the fold line 26, that is having the outer end thereof inclined towards the bow section 20. A longitudinal fold line or keel line 32 is provided and generally is along the longitudinal center of the blank and forms the keel portion of the boat and the blank 18 is symmetrical on both sides of the longitudinal line 32.

The stern section 24 is provided with a fold line 34 extending longitudinally of the blank and intersecting the inner end of the fold line 28. A diagonal fold line 36 extends from the point of intersection between the fold lines 28 and 34 and extends to the outer side edge of the blank 18 in spaced relation to the rear edge of the stern section 24.

The central hull section 22 is provided with a longitudinal fold line 38 forming an extension of the fold line 34 in the stern section and the fold line 38 extends substantially to the fold line 36 but terminates slightly in spaced relation thereto. Extending diagonally and forwardly from the point of intersection of the fold line 30 and the center fold line 32 is a fold line 40 which terminates adjacent to but slightly spaced from the terminal end of the fold line 38 and also in spaced relation to the fold line 26.

The bow section 20 is provided with a fold line 42 extending from the point of intersection between the fold line 26 and the center line 32 and extending in forwardly diverging relation to the fold line 26. The outer portion of the fold line 42 is designated by the numeral 44 and is angulated to a greater degree of divergence in relation to the fold line 26. A fold or crease line 46 extends from the outer end of the fold line 44 and extends diagonally to the point of intersection between the end edge of the bow section 20 and the center line 32. The blank 18 is symmetrical about the center line 32 and corresponding fold lines on either side of the center line are given the same reference numerals. Likewise, the areas defined by the fold lines will be given the same reference numerals.

The area of the bow section outwardly of the fold line 46 may be termed an upward deck section and is designated by the numeral 48 and is generally triangular in

configuration. The area defined by the center line 32, fold line 46, fold lines 42 and 44 is designated by the numeral 50 and forms one inclined side of the bow section 12. The area between the fold line 26 and the fold lines 42 and 44 is designated by the numeral 52 and forms a reverse fold or dart for permitting the angulation of the bow section and the central hull section in relation to each other.

The area of the central hull section 22 outwardly of the fold line 38 is designated by the reference numeral 54 and may be termed the gunwales in that it extends upwardly from the bottom section 56 enclosed by the fold lines 38, 40 and 30. The triangular area generally defined by the fold lines 40 and the fold line 26 is designated by the numeral 58 and is divided in half by the center line 32 and generally is downwardly curved and forms a continuation of the lower edge of the bow section 12 and forms the major portion of the bottom of the central hull section 14.

The stern 24 includes the transom 60 disposed between the fold lines 34 and rearwardly of the fold line 30 along with a triangular shaped foldable extension 62 and a trapezoidal shaped extension 64 which are separated by the fold line 36 and which are for folding into overlying relation to each other and against the rear surface of the transom 60.

In setting up the boat, the transom or stern section 60 is folded along the fold line 30 generally into perpendicular and arcuate relation as shown in FIGURE 2. The extension 62 along with the gunwale 54 is folded into a vertical position at which time the extension 64 will also be folded into a vertical position along the fold line 36 thus forming a double thickness triangular shaped extension for the gunwales 54 as illustrated in FIGURE 9. Due to the orientation of the terminal end of the fold line 36, the outer edge of the trapezoidal area 64 is disposed above the free edge of the triangular section 62 as shown in FIGURE 9. The double thickness triangular extension is then folded inwardly against the rear surface of the stern board 60 and the area of the stern board 60 and the area of the trapezoidal area 64 above the top edge of the triangular section 62 and above the top edge of the gunwale section 54 is folded downwardly in a reverse fold thus capturing the upper edge of the triangular section 62 and rigidly holding the same in position and also rigidifying the upper edge of the transom or stern member 60 thereby rigidifying the rear end of the boat.

The perpendicular orientation of the gunwale 54 is not carried throughout its length since the forward portion of the gunwales 54 inclines outwardly and the deck portions 56 are substantially horizontal although they may incline downwardly and outwardly slightly. The bottom section 58 is generally concave in configuration or substantially V-shaped in configuration as illustrated in FIGURE 8 and the fold line 26 is initially folded about the longitudinal center 32 and the fold line 42 and 44 is then folded into overlapping relation to the hull section as clearly illustrated in FIGURE 10 thus orientating the bow sections or areas 50 in inclined and converging relation which converge forwardly and diverge upwardly. The triangular sections 48 are then folded inwardly and are joined along a longitudinal line spaced above the longitudinal center with the adjacent edges when in folded condition being joined by a double outwardly facing channel shaped member 66 which is secured thereto by welding, soldering or the like 68, thus forming the only joint in the boat construction and, of course, this joint is well above the water line.

From the description of the blank and the manner in which the same is folded to form the boat, the construction of the boat is clearly apparent. The particular orientation of the bow section and the particular V-shaped configuration of the forward section of the central hull and the possible inverted V-shaped construction of the rear end of the hull provides for a minimum water drag when

the boat is moving at high speeds. As the speed of the boat increases, the particular construction of the hull is such that the bow section will ride up out of the water and only the central hull section will engage the water thus reducing the resistance to passage of the boat through the water. The blank 18 may be of suitable material such as sheet metal, various metallic alloys, steel screen or mesh, any fibrous material or cloth covered with or sprayed with fiber glass or plastic.

10 The foregoing is considered as illustrative only of the principles of the invention. Further, since numerous modifications and changes will readily occur to those skilled in the art, it is not desired to limit the invention to the exact construction and operation shown and described, 15 and accordingly, all suitable modifications and equivalents may be resorted to, falling within the scope of the invention as claimed.

What is claimed as new is as follows:

1. A one-piece hull construction of sheet material 20 formed from a substantially rectangular blank by folding along predetermined fold lines, said blank including a central hull section at one end and a forward bow section at the other end, said bow section of said blank including a longitudinal fold and keel line along which said bow section is folded to form upwardly divergent sides, a pair of rearwardly diverging fold lines extending rearwardly from a point adjacent the juncture of said keel line and the forward end edge of said blank and defining forward and opposite side and generally triangular bow deck 25 sections folded backwardly over said sides and having the portions of the forward end edges of said blank disposed on opposite sides of said keel line and closely adjacent in generally parallel relation extending longitudinally of said blank above said keel line and between said sides, means securing the opposite side portions of the forward marginal end edge portion of said blank together, a pair of darts formed in said blank between said center hull section and said forward bow section, said darts comprising reversely folded portions of said blank, each dart including two superposed thicknesses of said blank and being generally triangular in plan with its base edge generally coinciding with the corresponding adjacent portions of the corresponding side edge of said blank and tapering inwardly to an apex at least closely adjacent said keel line at the rear end of said bow section, said darts inclining said keel line forwardly and upwardly relative to the rear portion of the longitudinal center axis of said blank and said central hull section of said blank, the center hull section of said blank including upwardly projecting sides forming continuations of the rear ends of the bow section sides.

2. The combination of claim 1 wherein said hull construction includes an upstanding transversely extending stern section, the entire hull construction being constructed of one-piece material.

3. The combination of claim 1 wherein said darts each are folded over the adjacent portions of said central hull section wherein they open rearwardly so as to form a shallow rearwardly opening step and its free edge portion extending transversely of the corresponding portion of said hull construction.

4. The combination of claim 1 wherein said hull construction includes an upstanding transversely extending stern section, the entire hull construction being constructed of one-piece material, said stern section comprising a transom, the opposite end edges of said transom and the rear edges of the sides of said central hull section being interconnected by a pair of triangular gussets, said gussets each being folded against the inner surface of the corresponding end of said transom thereby enabling said central hull section sides and said transom to be disposed generally in perpendicular relation and formed from a single flat blank of sheet metal.
